UNITED STATES PATENT OFFICE.

THOMAS I. TEMPLE, OF INDIANAPOLIS, INDIANA.

SIGNAL.

Application filed October 24, 1924. Serial No. 745,705.

To all whom it may concern:

Be it known that I, THOMAS I. TEMPLE, a citizen of the United States, and a resident of Indianapolis, county of Marion, and 5 State of Indiana, have invented a certain new and useful Signal; and I do hereby declare that the following is a full, clear, and exact description thereof, reference being had to the accompanying drawings, 10 in which like numerals refer to like parts.

This invention relates to a signal device of that type employed in intersections of streets for guiding the traffic around the corners and preventing the cutting of corners thereby, the same being an improvement over the structure disclosed in Letters 15 Patent No. 1,468,763, issued September 25, 1923.

One object of the invention resides in the 20 mounting of the signal elements in the device, whereby they will be yieldingly held in position so as to give upon being struck by a vehicle, and thereby eliminating the danger of being broken. This is accomplished 25 by means of a spring seat adapted to normally maintain them within the device, so as to slightly protrude therefrom, but permitting them to be readily forced within the projection of the device upon a 30 vehicle coming in contact therewith.

Another feature of the invention resides in the arrangement and construction of the signal element, whereby the lens portion thereof will deflect and spread the light 35 rays striking its outer surface so as to cause said light rays to be diffused within the inner chamber, the inner chamber being provided with a reflecting surface which will further cause the diffusion or spreading 40 of the light rays so as to illuminate the entire surface of the lens portion of the signal to the maximum degree.

The full nature of the invention will be understood from the accompanying drawings and the following description and claims:

In the drawings, Figure 1 is a perspective view of the signal device. Fig. 2 is a plan view thereof. Fig. 3 is a section taken on 50 the line 3-3 of Fig. 2. Fig. 4 is a plan view looking toward the rear surface of the lens. Fig. 5 is a central vertical section therethrough. Fig. 6 is a plan view looking at the reflecting surface of the cupped shape member. Fig. 7 is a central vertical section therethrough. Fig. 8 is a

perspective view showing a modified form of signal device. Fig. 9 is a large front elevation of one of the letters mounted therein. Fig. 10 is a section taken on the line 10-10 of Fig. 9.

In the drawings there is shown a signal device comprising a substantially hemispherical casting 10 having radially-extending signal-receiving projections 11 formed thereon. Said casting is provided with downwardly-extending lugs 12 for anchoring the same in the surface of the street in which it is mounted. The radially-extending projections 11 are provided with openings 13, and enclose a substantially cylindrical recess or barrel for reception of the signal element.

The signal element consists of a substantially cup-shaped member of appreciable depth having its outer periphery provided with a seat 14 for reception of the bull's eye lens 15. Said lens is provided with a convex outer surface and a convex inner surface of greater radius of curvature, said inner surface having formed thereon an annular diffusion ring 16 concentric with the annular edge of the lens. Said ring is formed to project inwardly from the inner surface of the lens and is slightly curved in cross section so that the thickness and curvature of the lens at that point will be increased and varied. Thus the light rays projected against the outer surface of the lens, and passing therethrough, will be directed at varying angles and accordingly diffused into the receiving chamber of the metallic cup-like member 17. The rear surface of the cup-like member 17, being spaced from the inner surface of the lens, is adapted to receive the light rays projected therethrough and cause the same to be reflected back through the lens. Said reflecting surface is comprised of a plurality of concentric rings 18 associated together so as to form a series of projections and depressions in cross section, thus causing the entire reflecting surface to be of a concentric wavy-like formation. This results in the light rays striking said surface being reflected at varying angles, thereby causing the spreading and diffusion thereof throughout the chamber formed by said member. By means of the spreading and diffusion of the light rays throughout the interior of said member, the entire surface of the lens will be equally illuminated,

although the rays may be projected thereon at an angle from one side thereof.

One of said cup-shaped members and lenses is mounted in each of said projecting portions 11 of the casting 10, so that the convex curved surface of the lens protrudes through the opening 13, and is prevented from passing therethrough by an annular retaining ring 19. The cup-shaped member 10 extends rearwardly towards the center of the casting and is yieldingly engaged by a spring 20 which is adapted to seat against a central retaining plug 21. By means of this arrangement the complete signal element is yieldingly retained in normal position so that the lens may protrude from its socket in the casting for receiving light rays directed toward it from the side, while being capable of receding within the casting for protection against breakage in event it is engaged by a vehicle. The central plug 21 is adapted to receive a bolt 22 having a T-head 23 for centrally anchoring the device to the ground, the casting being provided with a recess 24 for receiving a nut 25 adapted to screw on the threaded end of said bolt for removably securing the casting thereto and maintaining the central plug 21 in position against the tension of the 30 springs 20.

In the modified form shown in Figs. 8, 9 and 10, the casting 110 is provided with the projecting portions 111 for receiving the letters 115 in place of the bull's eye lens, said letters being formed with a curved projecting convex outer surface and a corresponding convex inner surface of greater radius of curvature, said inner surface being provided with a plurality of projecting diffusion ribs 116 formed thereon, as above described, and also being formed with rearwardly extending sides 117 for providing a light-receiving chamber of appreciable depth. Clamped about the beaded edge of the letter-forming lens there is a metallic reflecting surface 118 having longitudinally extending corrugations for causing the light rays projected

thereagainst to be spread laterally so as to illuminate the entire surface of the letter-forming lens.

The invention claimed is:

1. In a signal device, a signal element comprising a metallic cup-shaped reflecting member of substantial depth, a lens mounted in the open end of said member, and a plurality of concentric diffusion rings formed in the reflecting surface thereof and spaced from said lens for receiving and diffusing the light rays throughout said element. 50 55

2. In a signal device, a signal element comprising a metallic cup-shaped reflecting member of substantial depth, a lens mounted in the open end of said member, a plurality of concentric diffusion rings formed throughout the entire reflecting surface of said member and lying adjacent each other for providing alternate curved projections and recesses in cross section, whereby the light rays received by said surface will be 70 reflected and directed at varying angles so as to be caused to be spread and diffused throughout said member, and an annular diffusing and spreading ring formed on the inner surface of said lens adjacent the periphery thereof, said ring being curved in cross section so as to spread and diffuse the light rays passing through said lens from one side thereof. 75

3. A signal device comprising a base casting having radially extending chambers formed therein, a signal element adapted to seat in each of said chambers so that a portion thereof protrudes beyond said base casting, a central plug adapted to be removably inserted in said casting, and a spring mounted between said plug and each of said elements for normally maintaining them in seated position and permitting them to be forced into said casting for protection. 80 85 90

In witness whereof, I have hereunto affixed my signature.

THOMAS I. TEMPLE.
